UNITED STATES PATENT OFFICE.

SAMUEL ARTHUR JENNINGS, OF ST. LOUIS, MISSOURI, ASSIGNOR OF ONE-
THIRD TO EDWARD C. MEISSNER, OF SAME PLACE.

BELL-RINGING VALVE.

SPECIFICATION forming part of Letters Patent No. 543,250, dated July 23, 1895.

Application filed November 30, 1894. Serial No. 530,310. (No model.)

To all whom it may concern:

Be it known that I, SAMUEL ARTHUR JENNINGS, a subject of the Queen of Great Britain, residing at St. Louis, State of Missouri, have 5 invented certain new and useful Improvements in Bell-Ringing Valves, of which the following is a full, clear, and exact description, reference being had to the accompanying drawings, forming a part hereof.

10 My invention has relation to improvements in bell-ringers; and it consists in the novel arrangement and combination of parts more fully set forth in the specification and pointed out in the claims.

15 In the drawings, Figure 1 is a side elevation of a bell mounted in its frame, the bell being at the limit of its upward swing and in connection with the bell-operating device forming my invention. Fig. 2 is a middle vertical

20 longitudinal section taken through the valve-casing. Fig. 3 is a detail elevation of the main valve-stem. Fig. 4 is a section on the line *y y* of Fig. 3, showing the air-groove and the radial ports communicating with the hollow portion of the stem. Fig. 5 is a section on 25 line *xx* of Fig. 3, showing the lateral passages leading to the bottom of the air-groove; and Fig. 6 is a detached view of the nut which secures the main stem to the reciprocating 30 piston confined within the valve-casing.

The object of my invention is to construct a fluid-operated bell-ringer valve—that is, a valve which when properly harnessed to a locomotive-bell will ring the latter until such 35 time as the supply of air or similar fluid is shut off.

To this end I have devised a valve which combines simplicity of construction with exactness of operation, the number of the parts 40 of the valve being reduced to a minimum, thus reducing friction between the parts and making the valve quickly responsive to the various conditions under which the same operates. In detail it may be described as follows:

45 Referring to the drawings, the valve-casing is composed of an upper section 1 and a lower section 2, the meeting ends of the two sections being respectively interiorly and exteriorly 50 screw-threaded, by which means they are

screwed to one another, but limited by the annular shoulder 3 of the lower section. Within a suitable groove 4 adjacent to the inner inwardly-projecting edge 5 of the lower section is interposed and firmly held a guide 55 plate or disk 6 having a lower depending portion or ridge 7. Through a central opening of the guide-plate 6 passes the hollow or perforated portion of a reciprocating stem 8. The lower end 9 of the hollow portion of the 60 stem operates within a central opening in the base of the section 2 and within the tubular open exhaust extension 10 secured within the same, the parts being made air-tight by a suitable packing-ring 11, as shown in Fig. 2. 65 The stem is limited in its downward movement by the shoulder 14 striking the inner surface of the section 2. The head 15 at the upper end of the solid portion of the stem operates within a suitable cavity 16 of a reciprocating piston 17 in the section 1 of the 70 casing. The stem 8, with its head 15, is coupled to the hollow piston by means of a nut 18 having a lateral opening 19 adapted to receive the stem proper, as shown in Fig. 75 2. Suitable packing-rings 20 are interposed between the piston and the inner walls of the casing, as shown. The portion of the hollow part of the stem which passes through the guide-plate 6 is provided with a superficial 80 longitudinal air-groove 21, having lateral basal extensions 22 to better facilitate the initial passage of the air into it, the groove establishing, when the stem is in its lowest position, communication between the lower 85 and upper sections of the casing. The inner exhaust-passage 23 of the hollow portion of the stem establishes communication between the outer air and the section 1 through the ports 24 adjacent to the shoulder 25 formed 90 at the juncture of the solid and hollow portions of the stem.

The sectional view of the valve in Fig. 2 shows the relative position of the parts when the piston 17 has been forced to its highest 95 position by the action of the compressed air which has entered the casing 1 under the surface of said piston. To the upper reduced end 26 of the piston is secured a fork 27, to which is pivoted the link 28, having a longi-

tudinal slot 29, within which is adapted to travel a pin 30 projecting from the crank-arm 31 secured to the bell-trunnion.

The valve-casing is secured to the bell-frame 32 by means of a bracket or arm 33, as best seen in Fig. 2. When the piston has been driven to its highest position, as indicated in Fig. 2, the position of the bell is as shown in Fig. 1. The bell now swings back to its vertically-hanging position. As it does so it drives the piston 17 downward, during which time the air within the chamber of the section 1 is exhausting through the ports 24, passage 23, and exhaust extension 10 into the atmosphere. Finally, as the piston descends the nut 18 strikes the shoulder 25, as shown in dotted lines in Fig. 2, forcing the stem downward sufficiently to establish communication between the chambers of the sections 1 and 2 via the groove 21, the bell itself by its momentum having by this time passed a slight distance to the left of its vertically-hanging position. Compressed air now passes through the pipe 34 and inlet 35 of the section 2 into the chamber of said section, thence via the groove 21 under the piston 17, forcing the latter up and carrying the bell to its highest position on the left of its vertically-hanging position. Then by the upward stroke of the piston the nut 18 (just before the piston has reached the limit of its upward stroke) engages with the head 15, forming part of the stem 8, raising the latter sufficiently to close the communication between the chambers of the sections 1 and 2 and opening the exhaust passages, as shown in Fig. 2, when the parts are once more in position for a repetition of the previous operation.

When the stem is in its highest position—that is, when communication between the two sections of the casing is closed—the bevel-shoulder 36 on the hollow portion of the stem has a seat on the correspondingly-beveled surface formed at the edge of the opening in the depending portion or ridge 7 of the guide-plate. The plate 6 forms a working joint at all times for the reciprocating stem, and when said stem is in its highest position, as indicated in Fig. 2, the plate forms an absolute seat for said stem.

37 represents a spring-controlled rod, whose

terminal nut 38 slides in the slot 29 and is adapted to be struck by the pin 30 during the ringing of the bell, this arrangement taking up any violent jar in case the driving pressure becomes too great.

Having described my invention, what I claim is—

1. In a bell ringing valve, a suitable casing having an upper and lower section; a perforated guide plate and valve seat separating the two sections, a stem having a hollow portion operating within the guide plate, an exhaust passage in said hollow portion establishing communication between the upper section and the outer air, a superficial groove on the hollow portion for establishing communication between the two sections, and a piston in the upper section controlling the action of the stem, substantially as set forth. 70

2. A bell ringing valve comprising a casing having a lower and an upper section, a guide plate separating the two sections, a stem having a solid and hollow portion passing through the guide plate, a terminal head carried by the solid portion of the stem, a reciprocating piston within the upper section of the casing having a cavity for the reception of the head of the stem, a retaining nut having a lateral opening for securing the stem to the piston, a shoulder at the juncture of the solid and hollow portions against which the nut is adapted to strike, a superficial longitudinal groove having lateral basal extensions on the hollow portion of the stem, a central exhaust passage in the hollow portion of the stem, ports leading from said passage and adapted to establish communication between the upper section and the outer air, an exhaust tubular extension leading from the base of the lower section, a suitable air inlet opening for the lower section, and a shoulder on the exterior of the hollow portion of the stem in the lower section for limiting the movement of the stem in one direction, substantially as set forth. 85

In testimony whereof I affix my signature in presence of two witnesses.

SAMUEL ARTHUR JENNINGS.
